PATENTED MAR. 3, 1908.

S. A. REEVE.

VARIABLE CLEARANCE ENGINE.

APPLICATION FILED OCT. 11, 1905.

UNITED STATES PATENT OFFICE.

SIDNEY A. REEVE, OF WORCESTER, MASSACHUSETTS, ASSIGNOR TO CHARLES M. BROWN,
TRUSTEE, OF READING, MASSACHUSETTS.

VARIABLE-CLEARANCE ENGINE.

No. 880,825.

Specification of Letters Patent. Patented March 3, 1908.

Application filed October 11, 1905. Serial No. 282,251.

To all whom it may concern:

Be it known that I, SIDNEY A. REEVE, a citizen of the United States, residing at Worcester, in the county of Worcester and State of Massachusetts, have invented certain new and useful Improvements in Variable-Clearance Engines, of which the following specification and accompanying drawings illustrate the invention in a form which I now regard as the best out of the various forms in which it may be embodied.

This invention relates to explosion engines of the type in which the volume of the clearance space at the end of the cylinder is varied in accordance with the load in order to preserve and improve the efficiency at moderate loads.

The invention also applies to compressors.

In the illustrative embodiment which I have shown in the drawings the principal features are a hollow piston expanded by means of water-pressure within the same and contracted by the pressure of the explosion within the working cylinder, together with a pump for increasing the quantity of water within the piston, operated by a motor which is actuated by the water expelled from another compartment in the piston, there being a loaded valve used in connection with the pump whereby the pressure within the delivery-pipe of said pump is kept down to a predetermined point. The discharge from the pump-motor may if desired be usefully applied by carrying it to a cooling chamber through which the products of combustion from the main engine are passed in order that the motive mixture of steam and products of combustion may be employed in a second or low-pressure cylinder. This disposal of the pump-motor exhaust affords a certain useful regulation.

Of the accompanying drawings, Figure 1 represents a diagrammatic sectional view of an explosive engine constructed in accordance with my invention. Fig. 2 represents a cross-section of the piston, Fig. 3 represents a section on the line 3—3 of Fig. 2.

The same reference-characters represent the same parts in all the views. In the drawings 10 indicates the working cylinder of an explosion engine which I have for convenience shown of the two-cycle double-acting type in which initial compression of air and gas is performed in compressor

cylinders 11 12 outside of the main cylinder 55 and admitted to the working cylinder under control of valves 13 13 when the working piston 14 has uncovered the middle exhaust-port 15 at either end of the stroke. I have also shown the exhaust-port 15 connected 60 through a pipe 16 (of exaggerated length in the drawings) with the interior of a cooling chamber 17 in the lower part of which a body of water is automatically maintained at a predetermined level by means of an automatic level-controller 18 which actuates a feed-throttling valve 19. The exhaust from the working cylinder 10 vaporizes the water in cooling chamber 17 and creates a motive mixture of steam and products of combustion 70 which passes out of the upper end of cooling chamber 17 through a pipe 20 and is employed in a second or low-pressure engine 200 which may be an ordinary steam-engine. The combination just described is claimed in 75 separate applications Ser. No. 267,718 and Ser. No. 267,719. It will be understood that several of the advantages of my invention may be attained without using this cooling chamber and low-pressure cylinder and may 80 also be attained in connection with ordinary four-cycle engines, either single or double acting.

The piston 14 is provided with two chambers 21 22 separated by a central partition 25 and having movable outer walls in the shape of plungers or followers 23. Water leaves the chambers 21 22 through the interior of the hollow piston-rod 24 by way of a passage 25 therein which communicates at one end 90 with a water-jacket 26 in one of the cylinder-heads and at the other end opens into the respective chambers 21 22 through inlets controlled by check-valves 27 which prevent a back flow. Water enters the chambers 21 22 through a passage 28 in a hollow tail-rod 29, the outlets from said passage to the chambers being controlled by check-valves 30 and the supply to said passage being from a water-jacket 31 in the opposite cylinder-head. From water-jacket 26 a pipe 32 leads to a hydraulic motor 33 whose piston 34 drives the piston 35 of a pump 36. The latter draws water from a supply-tank 37 and discharges it to a pipe 38 leading into the other water-jacket 31 and also connected with the suction pipe 39 of the pump by means of a by-pass 40 containing a safety-

valve 41 set or loaded to release at a certain determinate pressure. The discharge from the hydraulic motor 33 may be led away to any locality, but I have shown it as conducted by way of a pipe 42 to the cooling-chamber feed-pipe 43 and to a waste-pipe 44 containing a loaded valve 45 set to release at a predetermined pressure.

46 46 are the usual igniting devices located at opposite ends of the working cylinder and operated by the engine in the usual manner at or near dead center, and 47 is a speed-governor driven by the engine and controlling the quantity of explosive charge 15 by any of the usual methods, as for example by regulating the time of closing of the compressor admission-valves.

The operation of the apparatus is as follows: The charges are initially compressed 20 in the compressors 11 12 and admitted to either end of the working cylinder 10 at the end of the stroke, driving out the remaining exhaust gases through exhaust port 15 under sufficient back-pressure to enable them to 25 do work in the low-pressure cylinder. On the return stroke a charge is compressed and ignited at or near dead-center in the usual manner, the explosions being alternate in the two ends of the cylinder here shown. 30 The spring of the by-pass valve 41 is set to a pressure considerably higher than the pressure prevailing in the working cylinder when the exhaust-port 15 is uncovered, but considerably lower than the maximum pressure 35 of explosion and preferably lower than the highest compression-pressure reached within the cylinder before admission. Explosion occurs in one end of the cylinder when the pressure in the other end is at a minimum 40 and this explosion pressure besides driving the piston 14 in the usual manner causes 45 the expulsion of the water from chamber 21 or 22 by way of the corresponding valve 27 through the piston-rod 24 into the conduit 32 whereby the expelled water enters pump-motor 33 and drives the piston 34 of the latter. Piston 35 of pump 36 is considerably 50 larger in area than the motor-piston 34, the ratio being such that the resulting pressure 55 in pipe 38 will be approximately the pressure at which valve 41 is set to release, being sometimes above this pressure and sometimes below it. When the pressure delivered by the pump is above the release pressure 60 some water from the pump is by-passed around to the suction side and travels in a circuit, whereas if the pressure in pipe 38 is below the release pressure of valve 41 a volume of water will be delivered to one of the 65 piston chambers 21 22 on the non-exploding side, which volume is largely in excess of the volume expressed from the explosion side of the piston, owing to the excess of area of piston 35 over piston 34. This results in 70 maintaining a substantially constant average

pressure of explosion in the working cylinder. The standard is determined by the set of by-pass valve 41. If an increased quantity of charge is admitted to the cylinder 10, resulting in an explosion pressure above the standard, the pump 33 will be driven at a rate to raise the pressure in pipe 38 above the release pressure. Some of the pump delivery being thus by-passed, only a part of it reaches the opposite chamber of piston 75 14 and consequently the latter collapses relatively to what its volume would otherwise be. Hence the next exploding charge in this enlarged cylinder-end or clearance-chamber will afford a reduced maximum 80 pressure, nearer to the standard. On the other hand should the explosion pressure be below the standard, owing to reduced charge, the motive force in pump motor 33 would be less and the pressure in pipe 38 would be 85 below the release pressure of valve 41 and all of the pump delivery would go to the piston-chamber 21 or 22 opposite the explosion end, and distend said chamber so as to reduce the clearance space to correspond 90 with the reduced charge. The quantity of charge is regulated according to the load by the governor 47, and variations in the quantity of charge produce variable explosion pressures which have the effect before mentioned. For a brief period however while the expansible working piston is changing its volume the engine is enabled to respond quickly to an increased demand for power 95 since the explosion pressure will be temporarily raised considerably above the standard. The higher the explosion pressure the longer will be the period of high pressure in the working cylinder and the greater the 100 expulsion of water from the piston, this increased circulation occurring at a time when a greater cooling effect on the cylinder walls 105 is desirable.

By employing the cooling chamber 17 and its connections, a certain added result is attained, which, though not essential, I regard as useful. Water expelled from the pump-motor 33 is employed to feed the cooling chamber 17 under the control of the level-regulator 18, and the excess not needed 110 therein passes to waste or elsewhere through the valve 45 which is of course set to a pressure equal to or above that maintained in the cooling chamber 17. The difference between the back-pressure in the pipe 42 and the impressed pressure in pipe 32 represents the effective pressure available for work on piston 34. The opening of valve 45 may be quite small relatively to the opening of the level-regulator valve 19 so that the variations in the resistance and back pressure afforded by said valve 19, corresponding 115 with the variations in consumption of water within the cooling chamber 17, will afford a 120 measure of the rapidity of water-circulation 125 130

in the piston 14. This consumption, through the usual governing devices (not shown) employed on the low-pressure engine will vary with the load and produce corresponding variations in the piston circulation.

In connection with a low-pressure cylinder or other means for producing back-pressure in the exhaust pipe of the primary engine I may so fit the followers 23 in their guides as to cause a leakage of water, greater or less in amount, from the interior of the piston into the cylinder, to pass out with the exhaust gases and cool the latter by vaporization. Such loose fitting of the followers will be readily understood without special illustration. On occasion this may be made the sole supply of water to these gases, and the cooling chamber 17 may then be deprived of its water-supply by relieving all tension on the spring of valve 45, or said chamber with its water-feeding devices may simply be omitted from the apparatus.

When the invention is applied to a compressor, the piston, instead of receiving the motive force of the charge in the cylinder, imparts motive force to the charge and in that case the compression pressure only is the actuating agency which causes the circulation of the water in the piston chambers. The term "pressure engine" used in the claims is intended to cover compressors as well as motors.*

I do not hold myself to the exact construction shown, as various equivalents and modifications may be used. For example, instead of using an expandable chamber or chambers in the working piston, I may place the same in the cylinder head or heads, although the arrangement illustrated is preferred. I believe myself however to be the first to adjust the clearance automatically by means of a piston of variable volume, substantially as shown. It is not essential to the hydraulic variation that the release should occur through a pump motor. The release might occur otherwise and the piston 35 of the pump be actuated in a suitable manner, as for instance from the cross head of the main engine. Then could take place the admission of a constant quantity of liquid to the piston per unit of time or per cycle of the engine, with a variable release.

What I claim as new and desire to secure by Letters Patent is:

1. A pressure-engine formed with a plurality of variable cylinder-clearance chambers one of which is expandable by the fluid-pressure in said cylinder, and means actuated by the expansion of the last-said clearance chamber for varying the capacity of another of said clearance chambers.

2. An explosion-engine formed with a plurality of variable cylinder-clearance-chambers one of which is expandable by the explosion pressure in said cylinder, means for in-

termittently exploding combustible charges in said cylinder, and means actuated by the expansion of the last-said chamber for varying the capacity of another of said clearance-chambers.

70

3. A pressure-engine comprising a double-acting working-cylinder structure, a solid-piston structure working therein and axially expandible and collapsible at both ends, and means for varying the volume of one piston-end by the fluid-pressures active on the other piston-end.

75

4. A pressure-engine comprising a working cylinder, a hollow working piston therein having an axially movable wall with a liquid-chamber behind it for varying the piston-volume, and means for introducing liquid to said chamber from outside of the cylinder.

80

5. A pressure-engine comprising a working cylinder, a hollow axially expandible and collapsible working piston therein, a piston-rod connected with said piston and having a duct for conducting liquid between the exterior of the cylinder and the interior of the piston, and an external liquid pump connected with said duct.

85

6. A pressure-engine having a double-acting cylinder, a working piston therein having movable heads at both ends for varying the cylinder clearances, piston-rods at both ends extending through the cylinder-heads and having ducts for conducting fluid to and from the interior of the piston, and a connection between the rods for transmitting the force of the fluid-pressure between the ends of the piston.

90

7. A pressure-engine including a chamber having a movable clearance-varying wall, conduits for conducting fluid to and away from said chamber, and check-valves in said conduits permitting flow only in one direction in one of the conduits and only in the opposite direction in the other conduit.

95

8. A pressure-engine having a working-cylinder, a hollow working piston of variable volume therein, and means to supply a liquid to the interior of said piston at a pressure intermediate between the highest and lowest pressures prevailing in said cylinder.

100

9. A pressure-engine comprising a working cylinder having a variable clearance-space containing a liquid, an external hydraulic motor operated by enlargement of said space for performing a useful function in the engine, and means for conducting the liquid between said space and motor.

115

10. A pressure-engine comprising a working-cylinder having a variable clearance-space, a hydraulic motor operated by enlargement of said space, and means operated by said motor for varying another clearance space in the engine.

120

11. A pressure-engine having a plurality of clearance-varying chambers, means for conducting liquid to and from said chambers, a

125

130

motor operated by liquid expressed from said chambers, and a pump operated by the motor for supplying liquid to said chambers.

12. A pressure-engine having a plurality of clearance-varying liquid-chambers, means for expressing liquid from either of said chambers by the working pressure of the engine, and means for supplying to the other chamber by the force of the expressed liquid 10 a volume of liquid greater than the volume expressed.

13. A pressure-engine comprising a working cylinder having one or more clearance-varying chambers, conduits for leading water 15 to and away from said chambers, and means whereby the water leaving said chambers returns to the chambers another volume of water.

14. A pressure-engine comprising an expandible and collapsible working piston, conduits for leading water to and away from said piston, and means whereby the water leaving the piston may return to the piston a volume 20 of water greater than itself.

25 15. A pressure-engine having hydraulic clearance-varying devices, means for leading water to and away from said devices, means actuated by the leaving water for returning another volume of water to said devices, and 30 means for varying the proportion which the quantity returned bears to the quantity expelled, in accordance with the pressure of the water expelled.

35 16. An explosion engine comprising a working cylinder, a clearance-varying liquid-chamber therefor, a pump variably actuated

in accordance with the explosion pressure for supplying liquid to said chamber, and means for releasing at a point anterior to said chamber a portion of the delivery of said 40 pump upon the attainment of a predetermined pressure of the liquid delivered.

17. A pressure-engine having a clearance-varying chamber, a pump to supply liquid thereto, a delivery conduit connecting said 45 pump and chamber and having a branch outlet, and an automatic loaded release-valve controlling said outlet.

18. A pressure-engine having a plurality of clearance-varying liquid chambers, a 50 hydraulic motor operated by liquid expressed from said chambers, and a pump operated by said motor for supplying liquid to said chambers and having a greater capacity per cycle than the motor. 55

19: An explosion-engine having a plurality of clearance-varying chambers, conduits for leading water to and from said chambers, a hydraulic motor supplied by the outlet conduit, a pump operated by said motor for 60 supplying the inlet conduit and having a greater capacity per cycle than the motor, a by-pass from the pump-delivery to the pump-suction, and a loaded release-valve in 65 said by-pass.

In testimony whereof I have hereunto set my hand in the presence of two subscribing witnesses, the ninth day of September 1905.

SIDNEY A. REEVE.
